(57) **CLAIM**

The ornamental design for a mattress, as shown and described.

DESCRIPTION

The patent or application file contains at least one drawing executed in color. Copies of this patent or patent application

publication with color drawings(s) will be provided by the Office upon request and payment of the necessary fee.

FIG. 1 is a top front perspective view of a first embodiment of a queen mattress showing the new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top front perspective view of an alternate embodiment of a twin mattress showing the new design;

FIG. 9 is a front elevational view thereof;

FIG. 10 is a back elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a top front perspective view of an alternate embodiment of a twin XL mattress showing the new design;

FIG. 16 is a front elevational view thereof;

FIG. 17 is a back elevational view thereof;

FIG. 18 is a left side elevational view thereof;

FIG. 19 is a right side elevational view thereof;

FIG. 20 is a top plan view thereof;

FIG. 21 is a bottom plan view thereof;

FIG. 22 is a top front perspective view of an alternate embodiment of a full mattress showing the new design;

FIG. 23 is a front elevational view thereof;

FIG. 24 is a back elevational view thereof;

FIG. 25 is a left side elevational view thereof;

FIG. 26 is a right side elevational view thereof;

FIG. 27 is a top plan view thereof;

FIG. 28 is a bottom plan view thereof;

FIG. 29 is a top front perspective view of an alternate embodiment of a king mattress showing the new design;

FIG. 30 is a front elevational view thereof;

FIG. 31 is a back elevational view thereof;

FIG. 32 is a left side elevational view thereof;

FIG. 33 is a right side elevational view thereof;

FIG. 34 is a top plan view thereof;

FIG. 35 is a bottom plan view thereof;

(Continued)

FIG. 36 is a top front perspective view of an alternate embodiment of a California king mattress showing the new design;

FIG. 37 is a front elevational view thereof;

FIG. 38 is a back elevational view thereof;

FIG. 39 is a left side elevational view thereof;

FIG. 40 is a right side elevational view thereof;

FIG. 41 is a top plan view thereof;

FIG. 42 is a bottom plan view thereof;

FIG. 43 is a top plan view of a portion of the California king mattress, as indicated in FIG. 41; and,

FIG. 44 is a bottom plan view of a portion of the California king mattress, as indicated in FIG. 42.

The broken lines shown in the drawings form no part of the claimed design.
